UNITED STATES PATENT OFFICE.

WILLIAM H. PAIGE, OF SPRINGFIELD, MASSACHUSETTS, ASSIGNOR OF ONE-HALF TO DANIEL D. WARREN, OF SAME PLACE.

SLEEPING-CAR.

SPECIFICATION forming part of Letters Patent No. 288,361, dated November 13, 1883.

Application filed October 30, 1882. Renewed September 24, 1883. (No model.)

To all whom it may concern:

Be it known that I, WILLIAM H. PAIGE, of Springfield, in the county of Hampden and State of Massachusetts, have invented a new and useful Improvement in Sleeping-Berth Apparatus for Railway-Cars, of which the following is a specification and description.

The object of my invention is to provide a railway-car having no permanent seats therein, with apparatus for suspending sleeping-berths therein, which may be quickly set up and beds made thereon, and the car converted into a sleeping-car, and which may be as quickly taken down and packed away, and the car left with its floor unoccupied, to receive the portable chairs, and the car converted into a day-car; and I accomplish this by the means substantially as hereinafter described and illustrated in the accompanying drawings, in which—

Figure I is an elevation of a portion of the inside wall of a car, at the side, showing one section of the apparatus set up, upon which to suspend the beds. Fig. II is an inside view 25 of the upper end of one of the posts, showing the rail-bearings, and also the mechanism for securing and tightening the webs for supporting the bedding. Fig. III is a vertical section at line A of Fig. II, showing the bearing of 30 the tightening-roll in the post and the ratchet-and-pawl mechanism for holding the roll in the position into which it is turned. Fig. IV is a front view of the wall-bracket which supports the inner or wall end of the tightening-roll. Fig. V is a horizontal section of the same at line C of Fig. IV. Fig. VI is a vertical transverse section of the same at line D of Fig. IV. Fig. VII is a longitudinal section 35 of the inner or wall end of the tightening-roll at its axis, and Fig. VIII is a side and end view of the pawl which engages with the ratchet on the tightening-roll.

My apparatus for supporting the beds for sleeping purposes, as hereinafter described, is to be used in a railway-car constructed in 45 general as ordinary day-cars are constructed, but without any permanent seats, so the whole of the floor in the main saloon of the car is unoccupied except when used as a day-car, in 50 which case portable chairs, which may be of any desired construction to fold into a small

compass, may be brought in and placed upon the floor without any particular order or arrangement. When the car is to be used as a sleeping-car, the chairs are to be folded and packed away in a small apartment at one end of the car for that purpose. 55

In the drawings, F in Fig. I represents the interior of the side wall of a railway-car having my invention applied, into the floor of which, at the proper distances apart and at the proper distance from the side wall, are fitted and secured a series of plates, 5, provided with a vertical hole, and beneath this plate is first made a cavity, 40, as shown in Fig. III.

The uprights or posts for the apparatus consist of a base, as 4, provided with a curved toe, as 6, adapted to enter the hole through the plate 5, so that when the base has a firm bearing on the plate the end of the toe extends beneath an overhanging part of the cavity, by which, when the post stands upright, it is thereby held firm in that position. The main body of the post may be in the form of a tube, as 1, whose lower end is screwed into or otherwise secured in the base 4, and whose upper end is similarly secured in a casting, as 7, at a suitable height to support the web for the lower bed or berth, as shown in Figs. II and III, the casting at this part of the post and that at the top being precisely alike in general form and construction. This casting 7 is provided on opposite sides with a bracket, consisting of a semicircular flange, 3, below, and with an opening above it, so that the end of a tubular or cylindrical rail, 2, may be dropped into the opening from above and rest upon the upper side of this flange 3, as shown at the left in Fig. II; and I use two of these rails in each section, one extending alongside the lower bed or berth, with its ends resting in the lower castings 7, of two adjacent posts, and the ends of the other resting in the castings 7 of the same posts at the top. Two 95 supporting-plates, as 16, each provided with two buttons or studs, as 22, are secured to the wall of the car inside each plate opposite each casting 7 of the post, one above and the other below, and this plate has a hole through it, as 17, which is elongated vertically, and with an inwardly-projecting flange encircling the hole 100

of a little less diameter than the elongated hole in a vertical direction, as shown clearly in Figs. IV, V, and VI. The castings 7 are made hollow, as shown in Fig. III, and the 5 side facing the wall of the car is provided with a circular hole, as 34, and directly opposite, on the outside, a hole, as 11, preferably somewhat smaller in diameter, as shown in Fig. III, and the tightening-roll, as 8, I make preferably of 10 a tubular form, with a ratchet-head, 12, firmly secured in the end of the tube by a pin, 13, or by other suitable means. The extreme outer end of this ratchet-head 12 is made cylindrical, and has its bearing in the hole 11 in the 15 outer side of the casting, and just inside this hole the head is a little larger in diameter, with a series of ratchet-teeth, as 10, cut thereon, and inside the teeth an annular groove, 9, is made in the head, and inside this groove 20 the head is enlarged again, to have a bearing and revolve in the hole 34 through the inner side of the head. A stud or button, 22, similar to that shown on the plate 16, is made on the inner face of the casting 7, and a pawl, 20, 25 provided with a downwardly-projecting flange, 33, on one side, is pivoted in the casting at 31, so that its free end may hang down upon and engage with the ratchet-teeth 10 on the outside of the head, and with the flange 33 of the pawl 30 projecting down into the annular groove 9 in the head. Each post is extended upward by a tube, 1, screwed or secured in the top of the lower casting 7, and is similarly secured into the lower side of the upper casting 7, and the upper and lower castings 7 are made alike, as are also the ratchet-heads 12 of the upper and lower tightening-rolls, as well as the pawls, but with this exception—that to give the upper casting a little more finished appearance I 40 make a hole in the top of the upper casting 7, through which extends a short rod, 19, whose lower end is pivoted at 31 in the pawl 20, and in the lower casting, instead of this rod 19, I make a slot, as 21, through the inner face of the 45 casting, through which I turn a clamp-screw, 26, into a hole, 32, in the side of the pawl, both these arrangements being for the purpose of lifting the pawl from the outside to raise its flange 33 out of the annular groove 9 in the roller-head 12. A rectangular-shaped hole, 14, is made in the outer end of each roller-head 12, into which a winch having its end made to fit said hole is inserted by which to 50 turn the roller to tighten or loosen it.

55 Small brackets, as 25, may be secured along the inside of the car at proper distances apart, and when the car is to be used as a day-car one of the rails may be placed in the lower brackets, near the floor, and used to rest the 60 feet upon, and the other may be placed in the upper brackets, 25, extending along just below the windows, and used as a hand-rail, as shown in dotted lines in Fig. I.

When it is desired to take out the tightening-rolls 8, the ends are lifted out from the plates 16, and if the lower roll is being removed the screw 26 is raised in the slot 21 and

turned in, which raises the flange 33 of the annular groove 9 in the head 12, and the head 12 may then be withdrawn from the hole 34. 70 If the upper roll, 8, is being removed, the pawl may be raised by seizing the ball 29, secured to the upper end of the rod 19, and lifting the pawl to disengage its flange 33 from the groove 9, and the posts 1 are disengaged from the 75 plates 5, secured in the floor, and packed away in an apartment at the end of the car for that purpose.

In setting the apparatus up each post is put in place by holding it in an inclined position, 80 inserting the curved end of the toe 6 through the hole in the plate 5 set in the floor, and then bringing the post into an upright position. The heads 12 of the upper and lower tightening-rolls 8 are then inserted into their 85 respective holes 34 in the castings 7, and the pawls 20 are dropped into engagement with the ratchet-teeth, and with the flange 33 on each pawl engaging in its groove 9 on the head 12, which holds the head of the roll securely 90 in place in the casting, and the flange 15 on the opposite end of each roll 8, (which I prefer should be made on a casting secured in the end of the tubular roll,) is inserted into the upper part of the elongated hole 17 in the 95 plate 16, and the flange is then forced down into position behind the flange 18 on the plate 16 and around the lower part of the elongated hole.

One end of the webbing 24 may have a bar, 100 42, secured thereto, which bar is secured to a link, as 41, on each side, provided with an eye at the end, and one of these links on one side of the web, at one end, is placed on the button or stud 22 on the casting 7, and the link on the other side is placed on the stud or button 22 105 on the plate 16, secured to the side of the car, and the other end of the web is secured to the tightening-roll 8, extending from the next post, 1, to its plate on the side of the car, and 110 the roll is turned to tighten the web to the desired degree, and is there held by the ratchet and pawl.

A railway-car fitted in this way is especially 115 adapted to be used by parties traveling long distances, or for excursion parties, as the floor being unoccupied by permanent seats any portion may be used for any purpose desired—as for a piano or other instruments—and if there are comparatively few in the party only a corresponding number of chairs need be brought, and with plenty of room for other furniture, such as sofas or lounges; or little furniture may be used and more open space be left in which to move about.

125 It is evident that instead of the projection or flange, as 33, to engage in the annular groove 9 in the ratchet-head, a pin may be inserted through the hollow casting, as shown in dotted lines in Fig. III, to secure the roll to the post.

It is also obvious that instead of a stud or projection, as 22, and an eye, as 23, in the link 130 41, and an eye to engage with the stud, a small

shoulder or cavity may be made in the casting similar to that shown at 3, to support the rails 2, and a projection made on the link to engage in said shoulder or cavity.

5 In the construction of some cars—as, for example, those designed for excursion purposes—it may be desirable to provide for only one tier of berths, in which case only a single tightening-roll and a single web would be used, and 10 for other purposes—as for cars for construction purposes on a railway—three tiers of berths might be desired, in which case each post would be supplied with three castings, as 15 7, and a corresponding number of webs and tightening-rolls might be used.

Having thus described my invention, what I claim as new is—

1. The combination of a series of removable posts, each provided at its lower end with a 20 downwardly-projecting toe or lug, and a series of socket-plates, each provided with a cavity or aperture to receive said toe or lug, and secured to the floor of a railway-car, to furnish a bearing for the lower end of each post, substantially as described.

2. The combination of a series of removable posts, each adapted to be temporarily firmly secured to the floor of a railway-car, and hollow casting secured in said posts at a suitable 30 height to support the berth-webbing, and each provided with a web-fastening, a bracket provided with a web-fastening secured to the wall

of the car opposite each said casting, a tightening-roll flanged at one end, to be secured and revolve in said bracket, and a ratchet-head provided with an annular groove at the other end and adapted to be secured and revolve in said casting, and a pawl pivoted in each casting to engage with the teeth of said ratchet-head and with a fastening to engage in 40 said annular groove to hold the roll in its place, substantially as described.

3. In an apparatus for suspending the beds or couches in a railway-car, the combination of a tubular post having a hollow casting secured thereto at a suitable height to suspend the bed, said casting being provided with a fastening from which to suspend one side of the web, and adapted on opposite sides to receive the ends of longitudinal rails, a tubular 50 tightening-roll having a head secured in one end, and provided with an annular groove and with ratchet-teeth, and adapted at its outer end to receive a winch by which it is revolved, and a pawl pivoted in said casting, adapted to engage with the teeth and annular groove on said ratchet-head, and to be disengaged therefrom when it is desired to remove the roll from its bearing in the casting, substantially as described.
